UNITED STATES PATENT OFFICE.

ZACHARY T. HALL, OF PHILADELPHIA, PENNSYLVANIA.

DESIGN FOR A PLATE FOR STOVE-PIPE FLUES.

SPECIFICATION forming part of Design No. 17,458, dated July 19, 1887.

Application filed June 6, 1887. Serial No. 240,481. Term of patent 3½ years.

To all whom it may concern:

Be it known that I, ZACHARY T. HALL, a citizen of the United States, residing in the city and county of Philadelphia, State of Pennsylvania, have invented and produced a new and original Design for Plates for Stove-Pipe Flues, Collars, Stoppers, &c., of which the following is a specification, reference being had to the accompanying drawing, forming part thereof.

The leading feature of my design for a plate for stove-pipe flues, &c., is the breast with radial corrugations and rims encircling the same.

A represents a plate, having a breast, B, and central field, C. The breast has radial corrugations D, and is encircled by the rim E and bead F, the rim E being on the outer circumference of the breast, and the bead F on the

inner circumference thereof, or between the field C and corrugations D. The rim is plain 20 or plain-faced.

I claim—

1. A design for a plate for a stove-pipe flue, &c., comprising a central field, a breast with radial corrugations, and a rim outside of said 25 corrugations, substantially as described and shown.
2. A design for a plate for a stove-pipe flue, &c., herein shown and described, comprising a central field, a breast with corrugations, an 30 inner bead, and an outer plain rim.

ZACHARY T. HALL.
